PORTABLE INTERNAL COMBUSTION
ENGINE

Douglas R. Clarke, Toronto, Ontario, Canada

Original application August 30, 1937. Serial No.
161,652. Divided and this application March
21, 1938, Serial No. 197,281

6 Claims. (Cl. 123—195)

This invention relates generally to internal combustion engines of the type employed for marine purposes and is a division of my pending application Serial No. 161,652, filed August 30, 1937.

More particularly, the invention concerns itself with marine engines of the portable outboard type wherein the fuel tank is in the form of a casting supported between the cylinder of the internal combustion engine and the device for supplying fuel mixture to the cylinder. It is one of the principal objects of this invention to simplify engines of the above type by extending a passage from the cylinder through the fuel tank to the fuel mixture supplying device so that the fuel mixture is compelled to flow in heat conducting relation to the fuel in the tank before it is admitted to the cylinder of the engine. This construction not only avoids exterior plumbing, but also improves the operation of the engine in that it tends to maintain the fuel mixture at a more uniform temperature.

Another object of this invention consists in the provision of a marine engine of the type set forth in the preceding paragraph wherein the fuel tank is in the form of a casting demountably secured to the top of the cylinder casting and wherein both castings have passages cast integral therewith in a manner to register with one another in the assembled position of the parts to cooperate in forming the fuel mixture passage referred to above.

A further object of this invention consists in casting a lining in the fuel mixture passage so that the cross sectional area of the passage is uniform throughout its length and the walls of the passage are relatively smooth.

In addition to the foregoing, the present invention contemplates supporting the ignition coil above the fuel tank and extending the electrical conductors from the ignition coil to the igniter on the cylinder through a conduit cast into the fuel tank. This feature also offers the possibility of eliminating exterior plumbing or wires and not only simplifies the appearance of the engine, but insures protection for the electrical conductors.

The foregoing, as well as other objects, will be made more apparent as this description proceeds, especially when considered in connection with the accompanying drawing, wherein:

Figure 1 is a sectional view through a portable marine engine embodying the present invention; 55 Figure 2 is a cross sectional view taken sub-

stantially on the plane indicated by the line 2—2 of Figure 1; and

Figure 3 is a cross sectional view taken substantially on the plane indicated by the line 3—3 of Figure 1.

For the purpose of illustrating the present invention, I have selected a portable marine engine of the single cylinder outboard type operating on the two cycle principle and having provision for removably clamping the same to a boat to be propelled thereby. Upon reference to Figure 1, it will be noted that the engine proper comprises three castings, designated by the reference characters 15, 16, and 17. The intermediate casting 16 is detachably secured to the top casting 15 by means of suitable studs 18 and is similarly secured to the bottom casting 17 by means of the studs 19. The arrangement provides a unitary construction which is capable of being readily manufactured and assembled. The casting 15 is in the form of a fuel supply tank 20 having a top wall 21 forming a support for the ignition coil 22 and for the carburetor 23. The intermediate casting 16 is fashioned to provide a cylinder 24 at the lower end thereof and the bottom casting 17 is constructed to support a combined crankshaft and propeller shaft 25. The arrangement is such that the cylinder 24 of the engine is supported below the water level during operation of the engine in a manner that the same is effectively cooled by the transfer of heat from the cylinder to the surrounding water. As a consequence, the usual water jackets and circulating cooling system may be eliminated with the result that the weight of the engine, as well as the cost of manufacture, are substantially reduced.

The carburetor 23 is secured to the top wall 21 of the fuel tank casting 15 and supplies fuel mixture to the intake port 26 in the cylinder 24 through a passage 27 extending from the carburetor to the intake port 26 in the cylinder. In the present instance, a portion 28 of the passage 27 is cast integral with the fuel tank casting 15 and the remaining portion 29 of the passage is cast integral with the cylinder casting 16 in a manner to register with the portion 28 when the two castings are secured together by means of the fastener elements 18. A lining 30 is cast in the two portions of the passage 27 to provide the passage 27 with a uniform cross sectional area throughout its length and to also provide the passage with a smooth interior surface. As shown in Figure 1, the portion 28 of the fuel passage 27 is cast in one piece with the

fuel tank casting 15 in such a manner that the fuel contained in the tank surrounds the portion 28 of the passage and, as a result, the temperature of the fuel mixture flowing through the passage 27 is more uniform.

5 The ignition coil 22 is also secured to the top wall 21 of the tank and is connected to the distributor 31 and spark plug 32 by suitable electrical conductors 33. The distributor 31, as well 10 as the spark plug 32, are located in the cylinder casting 16 and the spark plug is secured to one side wall of the cylinder adjacent the upper end thereof to ignite the fuel mixture in the combustion chamber 34. The electrical conductors 33 extend upwardly from the distributor and spark plug through the cylinder casting 16 and fuel tank casting 15 to the coil 22. The conductors are sealed from the fuel in the tank 15 by means of a conduit 35 which extends through 15 the tank and is cast integral therewith. In this manner, the electrical conductors, as well as the spark plug and distributor, are completely concealed and protected from the weather. In this connection, it will also be noted that both the carburetor and ignition coil are enclosed by a cover 36 secured to the top wall 21 of the fuel tank casting 15 by fastener elements 37.

20 Upon reference to Figure 3, it will be noted that the side walls of the cover 36 are slotted adjacent the carburetor to provide ports 38 through which air is permitted to flow into the Venturi passage 39 of the carburetor. Fuel from the tank 15 is also supplied to the Venturi passage for mixture with the air through a jet 40 controlled by a needle valve 41 adjustably mounted to vary the area of the jet from zero to a predetermined maximum. The fuel is supplied to the jet from the tank through the medium of a conduit 42 having one end extending into the fuel tank to a point adjacent the bottom of the latter and having the opposite end communicating with the valve controlled jet. The volume of fuel mixture supplied by the carburetor is controlled by a throttle valve 43 mounted for 25 sliding movement transversely of the venturi 39 opposite the fuel jet 40 in a manner to vary the effective cross sectional area of the fuel mixture passage through the carburetor. The specific 30 construction of the valve and the manner in which the same operates is defined more in detail in my copending application Serial No. 268,977, filed April 20, 1939, and also constituting a division of the parent application Serial No. 161,652, filed August 30, 1937. With the above 35 construction, it will be noted that when the piston 46 in the cylinder 24 of the engine is on its suction stroke, fuel is drawn upwardly through the conduit 42 and is ejected into the air stream 40 passing through the venturi 39 so as to co-mingle with the air prior to being admitted to the intake port 26 in the cylinder 24 of the engine. When the piston 46 subsequently moves upwardly 45 on its compression stroke, the fuel mixture is compressed in the combustion chamber 34 and is ignited by the spark plug 32 in accordance with conventional practice. The increased pressure resulting from burning of the fuel mixture in the combustion chamber 34 forces the piston 50 downwardly on its power stroke and transmits a power impulse to the crankshaft 47 through the medium of the connecting rod 48. Inasmuch as the propeller 49 is directly secured to the crankshaft, it follows that reciprocation of the 55 piston effects the desired rotation of the pro-

peller. When the piston has completed its power stroke and is again moved upwardly, the products of combustion are exhausted from the cylinder into the conduit 50. The products of combustion are received by a muffler 51 and are exhausted from the muffler into a pipe 52 which extends below the level of the water so as to reduce the decibels of noise of operation to the minimum.

Thus, from the foregoing, it will be observed 10 that I have provided a marine engine of the outboard type composed of a relatively few simple parts capable of being inexpensively manufactured and assembled. It will also be noted that I have avoided exterior plumbing and exposed 15 ignition parts with the result that the engine not only presents a neater appearance, but is also more reliable in operation.

What I claim as my invention is:

1. In a marine engine, the combination with a 20 cast fuel tank and a cylinder located below the fuel tank having an intake port for fuel mixture, of a device supported on the top of the fuel tank and supplying fuel mixture to the intake port and communicating with the interior of the 25 tank to receive fuel therefrom, means for supplying air to said device for mixture with the fuel, and means for conducting fuel mixture from the device to the cylinder intake port including a passage extending through the fuel tank and 30 cast integral therewith.

2. In a marine engine, the combination with a cast fuel tank and a cylinder located below the fuel tank having an intake port for fuel mixture, of a device supported above the fuel 35 tank for supplying fuel mixture to the intake port of the cylinder, means for supplying fuel from the tank and air to said device, means for conducting fuel mixture from the device to the intake port in the cylinder including a passage 40 extending through the fuel tank and cast integral therewith, a conduit also extending through the fuel tank and cast integral therewith, and an ignition system having parts located above and below the fuel tank operatively connected by 45 means of electrical conductors extending through said conduit.

3. In a marine engine, the combination with a cast fuel tank, of a conduit extending through 50 the tank and cast integral therewith, and an ignition system having parts located above and below the fuel tank operatively connected by means of electrical conductors extending through the conduit.

4. In a marine engine, the combination with a casting having a cylinder therein provided with an intake port and a casting forming a fuel tank located above the cylinder casting, of a device supported above the fuel tank for supplying fuel mixture to the intake port in the cylinder, means for supplying fuel from the tank and air to the device, and means for conducting fuel mixture from the device to the intake port in the cylinder including a passage having a section 60 extending through the fuel tank in a manner to be surrounded by the fuel in the latter and cast integral with the fuel tank and also having a section cast integral with the cylinder casting in communication with the intake port 65 in the cylinder and registering with the section aforesaid.

5. In a marine engine, the combination with a casting having a cylinder therein provided with an intake port and a casting forming a fuel tank 70

located above the cylinder casting, of a device supported above the fuel tank for supplying fuel mixture to the intake port in the cylinder, means for supplying fuel from the tank and air to the device, means for conducting fuel mixture from the device to the intake port in the cylinder including a passage having a section extending through the fuel tank in a manner to be surrounded by the fuel in the latter and cast integral with the fuel tank and also having a section cast integral with the cylinder casting in communication with the intake port in the cylinder and registering with the section aforesaid, and a liner for the two sections of the pas-

sage having a uniform cross sectional area and a relatively smooth inner surface.

6. In a portable marine engine, the combination with a casting forming a fuel tank and a cylinder having an intake port, of means for supplying a fuel mixture to the intake port in the cylinder including a passage cast integral with the tank and extending through the latter in such a manner as to be surrounded by the fuel in the tank, and an ignition system for igniting the fuel mixture in the cylinder having electrical conductors extending through a conduit passing through the tank and cast integral therewith.
